CLAIM

The ornamental design for a portable charger device, substantially as shown and described.

DESCRIPTION

FIG. 1 is a bottom view of a modified embodiment of the portable charger device;

FIG. 2 is a left-side view of the modified embodiment of the portable charger device;

FIG. 3 front view of the modified embodiment of the portable charger device;

FIG. 4 is a right-side view of the modified embodiment of the portable charger device;

FIG. 5 is a back view of the modified embodiment of the portable charger device; and,

FIG. 6 is a top view of the modified embodiment of the portable device.

The features shown in broken lines depict portions of the portable charger device that form no part of the claimed design.

1 Claim, 2 Drawing Sheets(56)
